UNITED STATES PATENT OFFICE.

ARTHUR G. STENQUIST AND HENRY PROBALL, OF CHICAGO, ILLINOIS.

SAVINGS COIN BOX.

Application filed July 14, 1923. Serial No. 651,653.

- This invention relates to a coin box structure designed to facilitate the saving of money in small amounts by various persons and an object of the invention is to provide 5 a coin box structure adapted to be placed in factories or other places of employment which structure contains a plurality of coin receiving boxes numbered according to the employees of the establishment and into 10 which the respective persons may drop coins of any size and denomination whenever they desire and to have the saving coin boxes located in a conspicuous place to constantly remind the people of saving.
- 15 Another object of the invention is to provide a device as specified which can be opened only by a bank clerk or person authorized to open it and deposit the money from the various boxes to the accounts of the 20 respective individuals in a bank savings account and also to provide a device in which the various boxes are confined by a single door structure.

A further object of the invention is to 25 provide a structure for preventing the removal of coins or paper money from the boxes by inserting instruments through the coin receiving slot or openings.

Other objects of the invention will appear 30 in the following detailed description and in the accompanying drawings wherein:

Fig. 1 is a perspective view of my improved coin boxes and casing.

Fig. 2 is a vertical section through the casing structure.

Fig. 3 is a horizontal sectional view through the casing for containing the various coin boxes.

Fig. 4 is an enlarged front elevation of an 40 individual coin box.

Fig. 5 is a side elevation of an individual coin box partly in section.

Fig. 6 is a rear end view of an individual coin box.

Fig. 7 is a vertical sectional view through 45 the coin box taken on the line 7-7 of Fig. 5.

Fig. 8 is an enlarged sectional view taken on the line 8-8 of Fig. 7.

Referring more particularly to the drawing 50 the improved coin box structure comprises a casing 1 which is rectangular in shape and formed of any suitable sheet metal, preferably sheet steel, which will protect the contents of the casing from malicious 55 tampering therewith and also from fire. The casing 1 is adapted to be attached to any

suitable support at any convenient location where it will be frequently seen by the employees of the factory, office, or other mercantile establishment so as to remind them of saving. The casing 1 has a plurality of angle plates 2 supported therein in parallel pairs, one of each pair arranged at opposite sides of the casing as clearly shown in Fig. 3 of the drawing. The horizontal portions 60 3 of the angle plates 2 provide ledges for slidably supporting the coin boxes proper which are generically indicated by 5. All of the coin boxes are of similar construction, and are preferably struck from sheet steel 65 or analogous material and their front ends are adapted to have suitable advertising and individual indicia thereon. The front ends 7 of the individual boxes are provided with transversely extending slots 8 and with circular openings 9 which open out into the interior of the boxes so as to permit coins passed through the slots 8 to fall into the boxes. The circular openings 9 are provided 70 to permit bills or paper currency to be folded 75 and pushed into the boxes. Suitable means are provided for preventing the withdrawal of the coins or bills out of the box through the opening 9 or slot 8 by means of any type 80 of instrument and this means comprises a shaft 10 on which a plurality of arms 11 are mounted. The shaft 10 is rotatably supported against the interior of the front 7 of the box and it has springs 12 coiled thereabout.

The springs 12 have one of their ends engaging against the front side of the housing as shown at 13 and their ends 14 engaging the arms 11 to hold the arms yieldably over the slot 8 as clearly shown in Figs. 7 and 8 85 of the drawing. The springs 12 permit the arms 11 to be pushed inwardly into the box to allow coins to fall therein but they prevent the coins from being withdrawn out of the slots. A flat spring 15 has one end anchored 90 to a suitable rod 16 and it extends downwardly across the opening 9 to prevent the withdrawal of paper currency from the boxes 5. The boxes 5 are confined in the cabinet 1 by the front door 18 of the cabinet 100 which is hingedly supported in any suitable manner as indicated at 19 at the top of the cabinet but is provided with a plurality of rectangular openings 20 through which the front 7 of the boxes 5 are visible. The openings 20 are, however, of such size as to permit the adjacent portions of the door 18 to 105 engage about the front panel 6 of the front 110

7 of the boxes for securely confining the boxes in place within the cabinet. The door 18 may be held locked by any approved type of lock 21 the key of which is adapted to be held by a duly appointed official who alone is authorized to remove the coins and currency from the various coin boxes 5. The coin boxes 5 have a portion of their tops cut free but hingedly connected to the remainder of the box as shown at 22 forming the doors 23, which may be opened to permit the removal of the contents of the boxes 5. Spring fasteners 24 are carried by the doors 23 and engage suitable projections 25 struck outwardly from the rear ends 26 of the boxes to hold the covers or doors 23 closed.

It is, of course, to be understood that the invention may be constructed in various other manners and the parts associated in different relations and, therefore, we do not desire to be limited in any manner except as set forth in the claim hereunto appended.

Having thus described our invention what we claim is:

A device as set forth comprising a casing, 25 a plurality of supporting brackets within said casing and arranged in pairs, a plurality of individual receptacles slidably supported within the casing upon said brackets, a front door for said casing to permit the removal of said receptacles, said door provided with openings to permit access to the fronts of the individual receptacles but prevent removal of the receptacles from the casing, said individual receptacles provided with article receiving openings registering with the openings in the door, and spring pressed arms within said individual receptacles and extending at spaced points across the openings in the receptacles, each of said receptacles having a portion of its top formed into a door hingedly connected to the receptacle, and a spring clasp for normally holding said door closed.

In testimony whereof we affix our signatures.

ARTHUR G. STENQUIST.
HENRY PROBALL.
